A. B. CAMERON.
ORNAMENTAL PANEL.

No. 19,478.

Patented Dec. 10, 1889.

UNITED STATES PATENT OFFICE.

ALLAN B. CAMERON, OF WILLIAMSPORT, PENNSYLVANIA.

DESIGN FOR AN ORNAMENTAL PANEL.

SPECIFICATION forming part of **Design No. 19,478**, dated **December 10, 1889**.

Application filed November 12, 1889. Serial No. 330,083. Term of patent 14 years.

To all whom it may concern:

Be it known that I, ALLAN B. CAMERON, of Williamsport, Lycoming county, Pennsylvania, have invented and produced a new and original Design for Panels, of which the following is a specification, reference being had to the accompanying photograph, forming part hereof.

My design relates to a rectilinear panel having upon its surface the following ornamental configuration: Upon the surface of the panel, and extending to the edges thereof, appear a series of rectilinear channels A, radiating from the center B. Parallel to the channel C

appear channels D, equidistantly spaced, and parallel to the channel E appear channels F, also equidistantly spaced. The effect produced is that of numerous symmetrically-disposed elevations of various forms upon the surface of the panel, as shown. 15 20

I claim as my invention—

The design for an ornamental panel, substantially as herein shown and described.

ALLAN B. CAMERON.
